UNITED STATES PATENT OFFICE.

CHARLES V. NELLANY, OF NEW YORK, N. Y.

TOOTH-BRUSH.

1,142,356.

Specification of Letters Patent.

Patented June 8, 1915.

Application filed September 5, 1913. Serial No. 788,352.

To all whom it may concern:

Be it known that I, CHARLES V. NELLANY, of New York city, in the county of New York and State of New York, have invented certain new and useful Improvements in Tooth-Brushes; and I do hereby declare the following to be a full, clear, and exact description of the invention, such as will enable others skilled in the art to which it appertains to make and use the same.

My invention contemplates a tooth brush provided with a casing or compartment adapted to contain the brush proper or bristles when not in use, and forming part of the brush as an entirety.

In the accompanying drawings Figure 1 is a perspective view showing a tooth brush embodying my invention, the article being partly open. Fig. 2 shows the brush contained within the holder, the dotted lines indicating the position of the latter when the brush is in use. Fig. 3 is a section of the hinge or joint between the two elements forming the brush and Fig. 4 is a detail perspective thereof.

In the preferred form the brush comprises two parts 1 and 2, the former carrying the usual bristles 3. The parts 1 and 2 are connected by a hinge joint 4 and the part 2 carries or is formed with a housing or receptacle 5, adapted to receive the bristles 3 when the article is folded into the position illustrated in Fig. 2. In the construction described the bristles enter the receptacle in the direction of their length, that is,

their free ends first, and the receptacle protects all three sides of the bristles.

As appropriate means for hinging the two parts, I have shown the shank 6 of the part 1 within a sleeve 7 which is fulcrumed, by a pin 8, to a sleeve 9 on the shank of part 2, the sleeve 9 having ears 10 to receive the extremity of the sleeve 7. I have also shown the ears 10 formed with lugs 12 adapted to be received by a pair of notches 13, when the article is full open, and a similar pair of notches 14, when the brush is closed. A spring 15 is shown in Fig. 3 coiled around the pin 8. This spring tends to hold the sides of the sleeve 7 pressed outward and in consequence tends to maintain the lugs 12 in the notches 13 or 14.

I claim as my invention:—

As an article of manufacture a two-part tooth brush comprising a brush proper and a handle, each of said parts having a sleeve on the shank thereof, one of said sleeves having ears at its end and formed with a pair of lugs, and the other sleeve having two oppositely disposed pairs of notches to receive said lugs, a hinge pin forming the fulcrum for said shanks, and a spring coiled on said pin and tending to hold said lugs in said notches.

In testimony whereof, I have signed this specification in the presence of two subscribing witnesses.

CHARLES V. NELLANY.
